UNITED STATES PATENT OFFICE.

CHARLES E. DAVIS, OF CHICAGO, ILLINOIS, ASSIGNOR TO GOODMAN MANUFACTURING COMPANY, OF CHICAGO, ILLINOIS, A CORPORATION OF ILLINOIS.

APPARATUS FOR HANDLING LOOSE MATERIAL.

Application filed July 29, 1921, Serial No. 488,338. Renewed May 3, 1924.

To all whom it may concern:

Be it known that I, CHARLES E. DAVIS, a citizen of the United States, residing at Chicago, in the county of Cook and State of Illinois, have invented an Apparatus for Handling Loose Material, of which the following is a specification.

This invention relates to improvements in apparatus for handling ore and the like and 10 has for its principal object to provide a simple and durable conveying apparatus for transporting loose material from one place to another as, for instance, in a mine.

In prior applications for patent, one bearing Serial Number 382,696, filed May 28, 15 1920, and another bearing Serial Number 460,865, filed April 13, 1921, I have described an apparatus of the class above described comprising a scraper and a movable 20 frame adapted to form a support about which said scraper is guided. In the present application I utilize similar principles of construction and operation, but provide an improved construction which is particularly 25 adapted for use under conditions where the material is mined progressively along narrow entries, or "slices", as for instance, in iron ore mines. Under such conditions I find it desirable to provide supporting means for the head frame, or bearing 30 frame, about which the scraper is moved which means comprises a plurality of supporting arms adapted to extend laterally and engage mine props, or the side walls of 35 the slice or room. I also provide an improved construction of head frame.

My invention may be best understood by referring to the accompanying drawings in which Figure 1 is a top plan view of the 40 head frame and supporting means therefor.

Figure 2 is a view in side elevation of the apparatus shown in Figure 1.

Figure 3 is a vertical cross section taken on line 3—3 of Figure 2.

Figure 4 is a detailed cross section of a 45 clamping device for a lateral supporting arm.

Figure 5 is a fragmentary detailed view of a clamp forming a portion of the advancing 50 means.

Figure 6 is a detailed view of one form of lateral supporting arm which may be used with my apparatus.

Figure 7 is a top plan view illustrating 55 the use of the apparatus in a mine.

Figure 8 is a side view of the apparatus shown in Figure 7.

In the drawings, the head frame 1 comprises a horizontally disposed frame member 2 adapted to rest on the floor of the mine 60 and a second frame member 3 spaced vertically therefrom and having a vertically disposed rotatable bearing member, or roller, 4 mounted at the forward end of the frame on a shaft 5. The forward ends of the frame members 2 and 3 are curved to conform substantially with the shape of the roller 4 and the side members 6, 6 and 7, 7, respectively, of said frame members 2 and 3 both converge rearwardly as shown in Figure 1 and 65 are connected adjacent their rear ends by suitable vertical supports 8, 8. A preferred means of mounting the roller 4 and the shaft 5 on the frame is clearly shown in Figure 3 in which a cross-member 9 is connected to 70 opposite lateral faces of the lower frame member 2 and is provided with a centrally disposed boss 10 in which the lower end of the shaft 5 is supported, and a similarly disposed cross-member 11 connects opposite 75 faces of the upper frame member 3 and provides support for the upper end of the shaft 5. The roller 4 is provided with a hub 12 having an upper bearing sleeve 13 journaled on the shaft, and a lower bearing sleeve 14 of larger diameter than the upper bearing 80 and journaled on a collar 15 on the shaft. Said hub also carries a thrust bearing comprising an anti-friction ball bearing device 16 interposed between a shoulder 16 on the 85 hub, and a shoulder 18 on the collar 15. A sleeve 19 having an annular recess 20 therein is mounted on the upper end of the shaft 5 and is adapted to cooperate with an upwardly extending flange 21 formed on the 90 hub 12 to provide a dust proof bearing. Similar means for excluding dust are provided at the lower end of the hub 12 which means comprises an annular recess 22 formed in the hub, and an upwardly extending flange 23 mounted on the cross-member 9 and extending into said recess as shown. The body portion 27 of roller 4 is connected to hub 12 by suitable connecting pieces 24, 24 attached to flanges 25, 25 on said hub and 100 to circular end pieces 26, 26 of the roller.

Referring now to the means for supporting the head frame 1 it will be seen that a guide beam 30, preferably formed of an I-beam section is arranged horizontally and 110

longitudinally above said head frame and connected thereto by means affording relative longitudinal movement therebetween. In the embodiment illustrated this connecting means comprises a pair of upright hangers 31, 31 connected to the frame and each carrying thereon a pair of rollers 32, 32 engaging the under face of the beam 30 and a second pair of rollers 33, 33 adapted to engage the upper surface of the lower flange 34 of said beam. Means for affording relative movement of the head frame comprises a ratchet device 40 preferably mounted on the rear end of the head frame and provided with an operating handle 41 extending rearwardly in position to be readily operated. A flexible chain 42 is trained over the ratchet device and is attached to the beam 30 preferably by means of an adjustable clamping device 43, details of which are shown in Figure 5. This clamping device comprises a pair of inwardly extending jaws 44, 44 adapted to engage the lower flange 34 of the I-beam and movable thereon. The chain 42 is attached to a lever arm 45 pivotally connected to said clamping member and provided with a cam surface 46 which is brought into clamping engagement with the beam flange 34 when tension is applied to the chain 42. By means of this clamping arrangement just described the position of the chain 42 may be readily changed to any desired point along the beam 30. Supporting means for the beam 30 comprises a plurality of arms 50, 50 extending laterally therefrom and provided with end pieces 51 having suitable means for engaging mine props or the like. In Figure 1 these end pieces comprise a longitudinally disposed member having a concave outer face particularly adapted to engage a mine prop. In Figure 6 another form of engaging means is shown which comprises a convex plate 52 having projections thereon particularly adapted to engage the side wall of the mine. Each of the arms 50 are pivotally connected to a clamp 54 having longitudinal movement along the upper flange 35 of the beam 30 and adapted to be secured in place thereon by suitable means such as a screw 55 carried by a clamp 54 and provided with a handle 56. Said arms 50 are preferably connected to the clamp 54 by means of a removable pin 57 having a handle 58 for removing the same. The use and operation of the device described will be readily understood by references to Figures 7 and 8 which show a typical installation of the apparatus in a mine.

60 A room or entry having a top wall 60, bottom wall 61, and side walls 62, 62 is shown as being extended longitudinally by advancing the working face 63 at one end thereof. The material is dislodged or "shot down" 65 from the working face 63 into a pile of loose

material indicated at 64. Suitable mine props as indicated at 65, 65 are provided as the mining work progresses. In order to remove the loose material, my apparatus is positioned with the head frame 1 resting on the mine floor adjacent the front edge or "toe" of the pile 64. The guide-beam 30 comprising part of the supporting means is arranged in line with the direction in which the loading operation is to proceed, it being preferable, in commencing the loading operation, to have the forward end thereof extending in advance of the head frame 1. The beam 30 is secured in place by means of the laterally extending arms 50, 50 which may be adjusted to any desired position therealong by means of the clamps 54, 54, so as to engage the ends of the arms with the mine props 65, 65, to hold the guide beam substantially rigid. A scraper 70 having a head rope 71 and a tail rope 72, connected with a suitable hoisting device (not shown) for operating the same, is arranged so as to be reciprocably moved about the forward end of the head frame 1 and be directed into the pile of loose material 64 to gather a load. A preferred form of scraper for this purpose is shown in the drawings and has been described in my two pending applications already referred to above. One side of said scraper engages with the roller 4 while passing around the front end of the head frame at which portion of its journey the greatest resistance is usually encountered, viz., while the scraper is gathering its load. The head frame 1 is advanced as fast as the material is removed from the forward edge of the pile 64, so as to maintain the scraper in proper position to gather a load each time it moves about the head frame. The head frame is advanced by means of the ratchet device 40 operated by the handle 41 and connected with the chain 42 extending forward to the clamp 43, in the manner already described. When the head frame 1 approaches the forward end of the guide beam 30 during the progress of the work, said beam is advanced to a new position by disengaging the supporting arms 50, 50, and rolling the beam 30 forwardly the desired distance, where it is again secured in place by tightening the lateral supporting arms 50, 50 in the new position. The position of the clamp 43, associated with the ratchet device, may also be changed as desired along the beam 30.

In case the apparatus is used under conditions where it is preferable to engage one or more of the supporting arms 50 with the side walls 62, 62 rather than with a mine prop it will be understood that an arm having an end piece 52 as shown in Figure 6 may be substituted for the arm having end piece 51 as shown in Figures 7 and 8.

An apparatus constructed as above described presents several practical advantages.

- The arrangement of lateral supporting arms affords a rigid support for the head frame, which is particularly desirable in this type of loading device, which must withstand great lateral pressures. It is particularly adapted for use in places having a high roof such as illustrated in Figure 8, under which conditions it is often impracticable to provide supports extending to the roof.
- 10 The lateral supporting arms are readily adjustable so as to suit varying conditions as to position of props, width of place, etc. Said arms extend above the path of movement of the scraper so as not to interfere with its loading operation. The head frame 1 is readily advanced with respect to the guide beam 30 and, on the other hand, the guide beam 30, together with its lateral arms, may be easily advanced with respect to the frame when the beam is moved to a new position by reason of the arrangement of the rollers on the head frame 1, which provide a vertical support for said beam while it is being so advanced.
- 15 Having described my invention what I claim as new and desire to cover by Letters Patent is:
1. In combination with a draft operated scraper, a frame having a curved forward portion adapted to provide a lateral bearing for said scraper and means extending laterally above said curved bearing portion for supporting said frame with respect to fixed abutments.
2. In combination with a draft operated scraper, a frame having a curved forward portion adapted to provide a lateral bearing for said scraper, means extending laterally above said curved bearing portion for supporting said frame with respect to fixed abutments, and means affording longitudinal movement of said frame with respect to said supporting means.
3. In combination with a draft operated scraper, a frame having a curved forward portion adapted to provide a lateral bearing for said scraper, and means affording lateral support for said frame comprising a plurality of arms connected with said frame and adapted to extend laterally above said curved bearing portion.
4. In combination with a draft operated scraper, a frame having a curved forward portion adapted to provide a lateral bearing for said scraper, and a supporting member provided with a plurality of arms adapted to extend laterally above said curved bearing portion.
5. In combination with a draft operated scraper, a frame having a curved forward portion adapted to provide a lateral bearing for said scraper, a supporting member provided with a plurality of arms adapted to extend laterally above said curved bearing portion, and means affording longitudinal movement of said frame with respect to said supporting member.
6. In combination with a draft operated scraper, a frame having a curved forward portion adapted to provide a lateral bearing for said scraper, and a supporting member provided with a plurality of hinged arms adapted to extend laterally above said curved bearing portion.
7. In combination with a draft operated scraper, a frame having a curved forward portion adapted to provide a lateral bearing for said scraper and a supporting member provided with a plurality of hinged arms adapted to extend laterally above said curved bearing portion, said arms being adjustable longitudinally with respect to said supporting member.
8. In combination with a draft operated scraper, a frame having a curved forward portion adapted to provide a lateral bearing for said scraper, a supporting member provided with a plurality of hinged arms adapted to extend laterally above said curved bearing portion, said arms being adjustable longitudinally with respect to said supporting member, and means affording longitudinal movement of said frame with respect to said supporting member.
9. In combination with a draft operated scraper, a frame having a curved forward portion adapted to provide a lateral bearing for said scraper, a supporting member comprising a horizontal disposed beam, a plurality of arms connected to said beam and adapted to extend laterally above said frame, guide means affording longitudinal movement of said frame respective to said beam, and means for advancing said frame along said beam.
10. In combination with a draft operated scraper, a frame having a curved portion adapted to provide a lateral bearing for said scraper, a supporting member comprising a horizontally disposed, flanged beam, a plurality of hinged arms adjustable along the upper flange of said beam and adapted to extend laterally above said frame, and guide means affording longitudinal movement of said frame respective to said beam comprising a plurality of anti-friction members engaging the lower flange of said beam.
11. In combination with a draft operated scraper, a frame provided with vertically disposed roller at one end thereof adapted to form a lateral bearing for said scraper, a supporting member for said frame provided with a plurality of arms adapted to extend laterally above said roller, and means affording longitudinal movement of said frame and roller respective to said supporting member.
12. In combination with a frame adapted to afford lateral bearing for a draft operated

- scraper, a plurality of arms adapted to extend laterally above said frame, and means on the ends of said arms for engaging adjacent fixed abutments.
5. 13. In combination with a frame adapted to afford lateral bearing for a draft operated scraper, a plurality of arms adapted to extend laterally above said frame, and means on the ends of said arms for engaging adjacent fixed abutments, comprising a member having a substantially concave outer face.
10. 14. In combination with a frame adapted to afford lateral bearing for a draft operated scraper, a plurality of arms adapted to extend laterally above said frame, and means on the ends of said arms for engaging adjacent fixed abutments, comprising a member having a substantially convex outer face.
15. 15. In combination with a frame adapted to afford lateral bearing for a draft operated scraper, a plurality of arms adapted to extend laterally above said frame, and means on the ends of said arms for engaging adjacent fixed abutments, comprising a member having a substantially convex outer face provided with projections thereon.
20. 16. In combination with a frame adapted to afford lateral bearing for a draft operated scraper, a supporting member for said frame, a plurality of arms adapted to extend laterally from said supporting member to engage fixed abutments, and means for fixing said arms at various positions along said supporting means.
25. 17. In combination with a frame member adapted to operate on the ground, and affording lateral bearing for a draft oper-
- ated scraper, a guide member having laterally extending means adapted to engage fixed abutments, and means affording relative longitudinal movement of said frame and said guide members, comprising a plurality of hangers carried by one of said members and having oppositely disposed anti-friction rollers engaging upwardly and downwardly facing bearing surfaces carried by the other of said members.
30. 18. In an apparatus of the class described, a head frame adapted to operate on the ground, and comprising lower and upper frame members vertically spaced apart, a vertically disposed roller mounted at the forward end of said frame adapted to provide lateral bearing for a draft operated scraper, and means connected with the upper frame member for supporting said head frame and roller against lateral movement.
35. 19. In an apparatus of the class described a head frame adapted to operate on the ground, and comprising lower and upper frame members vertically spaced apart, a vertically disposed shaft mounted on and extending between said upper and lower frame members, and provided with a collar, a roller mounted on said shaft having a thrust bearing engaging said shaft collar, said roller being adapted to provide lateral bearing for a draft operated scraper, and means connected with the upper frame member for supporting the head frame and roller against lateral movement.
40. 65. 70. Signed at Chicago, Illinois, this 26th day of July, 1921.

CHARLES E. DAVIS.
